PORTABLE STOVE

Bestor Robinson, United States Army,
Oakland, Calif.

Application July 13, 1942, Serial No. 450,781

4 Claims. (Cl. 126—38)

(Granted under the act of March 3, 1883, as
amended April 30, 1928; 370 O. G. 757)

The invention described herein, if patented, may be manufactured and used by or for the Government for governmental purposes, without the payment to me of any royalty thereon.

The present invention relates to portable stoves, and is particularly concerned with miniature types of folding stoves such as are ordinarily used by ski or parachute troops, and carried as a part of issued military equipment. In this connection it may be pointed out that troops operating in mountains or cold climate regions must depend on miniature stoves of this general class for preparation of meals, et cetera, and since troops operating in cold climate regions do not ordinarily have any mechanized means of transportation, the stoves must necessarily be carried as a part of the individual packs of the soldiers. Under these circumstances, it is a first essential of equipment of this type that it be designed to occupy a minimum amount of space when packed and to be of relatively light weight.

It is, therefore, the principal object of the present invention to provide a collapsible miniature stove including a liquid fuel reservoir and burner in combination with a novel and improved stove frame including stove feet and means for supporting a cooking utensil above the stove burner.

A further object of the invention is a provision of a novel folding stove structure wherein the stove feet and utensil supporting means are arranged to be clustered closely about the burner and reservoir, so that the device will occupy a minimum amount of space while being carried in a soldier's pack.

A further object of the invention is a provision of a collapsible stove frame of unusual mechanical simplicity comprising a frame work consisting of formed wire, well adapted to economical methods of manufacture and capable of easy manipulation in use.

A further object of the invention resides in the provision of a collapsible stove frame comprising a plurality of pivoted wire supports, each including an extensible foot and a utensil support having a common pivotal mounting on the fuel reservoir of the stove.

A further object of the invention is the provision of a collapsible stove assembly including extensible feet having a relatively wide flat web-type supporting surface of sufficient area to provide firm support for the stove in snow or other non-solid substances.

Referring now more particularly to the draw-

ing attached to and forming a part of the present specification,

Fig. 1 is a side elevational view of a collapsible miniature stove constructed in accordance with the teachings of the present invention.

Fig. 2 is a plan view thereof, and

Fig. 3 is a fragmental side elevational view showing the stove feet and utensil supporting frame in nested position with respect to the stove reservoir and burner.

The stove comprises a fuel reservoir 10 having its lower end closed by reservoir bottom 11 united to the reservoir 10 by an overlapping marginal band 12. The reservoir 10 is also provided with a filler opening normally covered by the cap 13, and a small air pump 14 to build up air pressure in the reservoir for purposes well understood in the art to which the present invention relates. A burner tube 15, which includes a fuel shut-off valve 16 and a cleaning needle control handle 17, extends upwardly to a burner cup 18 which houses a conventional burner jet (not shown).

These structures, as thus far described, are quite conventional in the art and do not form the essence of the present invention, except in so far as they are a part of a combination with the collapsible leg and utensil supporting frame to be hereinafter described.

It will be understood, of course, that the purpose and function of the supporting frame is to provide a means for supporting a cooking utensil above and in proper space relationship with the burner cup 18, and also to provide supporting feet for the stove, to increase the effective area of support in order to prevent tipping and to provide a reasonably solid means of support on soft surfaces such as loosely packed snow. The utensil supporting frame comprises three identical main supports 21, each having a vertical portion 22 secured in pivotal relationship with a sheet metal bracket 23 soldered or otherwise secured to the band 12 of the fuel reservoir. The lower end of the support 21 extends outwardly from the lower end of the bracket into a leg extension 24 terminating in a relatively large loop 25 which is preferably closed by a thin sheet metal disk 26 soldered to its upward side. The disk 26 increases the area and supporting surface of the leg, so that the stove may be supported in snow without sinking deeply below the surface. The upper end of the support 21 consists of a riser portion 27 extending upwardly and angularly outwardly to a point slightly above the top of the burner cup 18. The upper end of the riser is provided with a loop 28, which interlocks with

end loops 29 on each of a pair of supporting rails 30. These rails 30 are arranged to extend inwardly from the upper end of the risers 27 to the burner cup 18, to provide a support for holding cooking utensils above the burner. The inner end of the rails 30 are offset downwardly at 31, so that the cooking vessel positioned on the stove will be held slightly above the top of the burner cup 18, and each of the rails is provided with a tip portion bent downwardly to engage and extend through punched openings in the marginal flange of the burner cup 18.

The operative position of the collapsible utensil supporting frame is illustrated in Figs. 1 and 2 of the drawing. When the several parts of the device are in this position, the engagement of the tips 32 of the top rails 30 with the burner cup 18 will maintain the risers 27 of the supporting brackets 21 in outwardly extended position, so that the legs and feet 25 of the stove will be spread apart to provide the greatest stability for the stove, and, of course, to provide a suitable support for a cooking utensil above the stove burner.

When the stove is not in use, the supporting assembly is collapsed by lifting the links 30 upwardly to disengage the tips 32 from the burner cup and then rotating each of the supports 21 in the bearing bracket 23 to the position shown in Fig. 3. In this position, the feet 25 nest closely against the lower surface of the bottom of the fuel reservoir and the risers 27 extend diagonally inwardly against the burner cup 18. The links 30 remain secured to the upper ends of the risers and will hang downwardly therefrom, as shown in Fig. 3, so that the entire utensil supporting assembly is clustered compactly around burner tube 15.

From the foregoing it will be apparent that the present invention provides a utensil supporting assembly and a miniature stove that combines the advantages of an extremely simple, cheap, and rugged structure, with the obvious advantages of a device of extremely light weight that may be easily manipulated in setting up or collapsing, and which is characterized by a complete structural assembly including no loose parts that may become mislaid or require retaining chains or similar devices to prevent loss. It will be also seen that the device of the present disclosure is advantageous by reason of its unusual simplicity and by reason of the fact that it is formed entirely of bent wire, so that it requires no expensive dies or forming tools for the production of stoves in quantities.

The drawing of the present application illustrates the details of a present preferred embodiment of the invention that is believed to best typify the teachings of this disclosure; but it is believed that the invention is capable of some alterations and modifications without departing from the inventive spirit, and it is accordingly requested that the scope of the inventive thought be regarded as limited only by the scope of the language of the appended claims.

Having thus described my invention, what I claim as new and desire to secure by Letters Patent is:

1. In a portable stove, a fuel reservoir and a burner in combination with a collapsible supporting structure comprising a plurality of identical wire supporting brackets, each pivotally connected to the stove reservoir at separate points circumferentially spaced about the reservoir; each

of said supporting brackets including a riser portion above the pivoted portion, said riser extending upwardly and diagonally outwardly and terminating in a top loop, a pair of top rails each having loops interconnecting with the top loop of the riser, and each including tip portions at right angles to the rails adapted to engage perforations in the upper surface of the stove burner; the arrangement being such that when said tip portions of the rails are engaged in said perforations the rails and supporting brackets will be maintained in assembled position and provide a support for a utensil above the burner, and so that when the tips of the rails are disengaged the supporting brackets may be pivoted into close clustered relationship around the stove burner.

2. In a portable stove, a fuel reservoir and a burner in combination with a collapsible supporting structure comprising a plurality of identical wire supporting brackets each pivotally connected to the stove reservoir at separate points circumferentially spaced about the reservoir; each of said supporting brackets including a riser portion above the pivoted portion, said riser extending upwardly and diagonally outwardly and terminating in a top loop, a pair of top rails each having loops interconnecting with the top loop of the riser, and each including portions adapted to engage the stove burner; the arrangement being such that when the rails are engaged with the burner the rails and supporting brackets will be maintained in assembled position and provide a support for a utensil above the burner.

3. In a portable stove, a fuel reservoir and a burner in combination with a collapsible supporting structure comprising a plurality of identical wire supporting brackets, each pivotally connected to the stove reservoir at separate points circumferentially spaced about the reservoir; each of said supporting brackets including a foot portion extending outwardly from the pivoted portion and terminating in a wide loop closed by a thin disk to provide a web of relatively large area and remote from the reservoir of the stove.

4. In a portable stove, a fuel reservoir and a burner in combination with a collapsible supporting structure comprising a plurality of identical wire supporting brackets, each pivotally connected to the stove reservoir at separate points circumferentially spaced about the reservoir; said pivots having their axes vertical and parallel to each other; each of said supporting brackets including a foot portion extending outwardly from the lower end of the pivoted portion and terminating in a wide loop closed by a thin disk to provide a web of relatively large area and remote from the reservoir of the stove; each of said supporting brackets including a riser portion above the pivoted portion, said riser extending upwardly and diagonally outwardly and terminating in a top loop, a pair of top rails each having loops interconnecting with the top loop of the riser, and each including tip portions at right angles to the rails adapted to engage the upper surface of the stove burner; the arrangement being such that when said tip portions of the rails are engaged the rails and supporting brackets will be maintained in assembled position and provide a support for a utensil above the burner, and so that when the tips of the rails are disengaged the supporting brackets may be pivoted into close clustered relationship around the stove burner.

BESTOR ROBINSON.
